176,310

BOTTLE STERILIZER

James Conlin and William Schulz, Reedsburg, Wis., assignors to HanksCraft Company, Reedsburg, Wis., a corporation of Wisconsin

Application July 30, 1954, Serial No. 31,683

Term of patent 14 years

(Cl. D81--10)

The figure is a perspective view of a bottle sterilizer embodying our new design. Both sides of the bottle sterilizer are alike.

We claim:

The ornamental design for a bottle sterilizer, as shown and described.

References Cited in the file of this patent

UNITED STATES PATENTS

D. 149,425	Kurrash	Apr. 27, 1948
D. 168,340	Gallay	Dec. 9, 1952